Patented Apr. 25, 1922.

UNITED STATES PATENT OFFICE.

WALTER L. GROSS, OF AUGUSTA, KANSAS.

VALVE STRUCTURE FOR WELL INSTALLATIONS.

1,413,909.

Specification of Letters Patent. Patented Apr. 25, 1922.

Application filed February 11, 1922. Serial No. 535,908.

To all whom it may concern:

Be it known that I, WALTER L. GROSS, a citizen of the United States, residing at Augusta, in the county of Butler and State 5 of Kansas, have invented certain new and useful Improvements in Valve Structures for Well Installations, of which the following is a specification, reference being had therein to the accompanying drawings.

10 This invention relates to valve structures for well installations and especially for deep wells, such as pumping oil wells and the like, and has for an object to provide a valve organization for pumping purposes 15 which may be readily and conveniently withdrawn from and inserted into the casing of a deep well as an organized structure.

15 A further object of the invention is to provide an improved type of valve organization which may be inserted into and withdrawn from a well casing of a deep well as such unitary structure, as distinguished from withdrawing the working valve and valve structure at one operation and then 25 withdrawing the standing valve at a second operation.

20 A further object of the invention is to provide an organization consisting of a standing valve and a working valve so connected that when the standing valve is properly seated ample working space is allowed for the reciprocation of the working valve without in any way disturbing the standing valve, but that when the working valve is 30 moved through a greater amplitude of movement than its normal working reciprocation, it will at the inserting movement seat the standing valve and at the withdrawing movement withdraw the standing valve, 35 leaving the casing clear.

40 With these and other objects in view the invention comprises certain novel parts, elements, units, combinations and functions, as shown in the drawing, together with mechanical equivalents thereof, as will be hereinafter more fully described and claimed.

In the drawings:

45 Figure 1 is a longitudinal vertical diametrical sectional view through a casing with the valve organization shown therein in side elevation and in pumping relation;

50 Figure 2 is a vertical diametrical sectional view through a casing showing the valve organization partly in side elevation and partly 55 in section and in relation for withdrawing the standing valve by the withdrawal of the

working valve under the action of the sucker rod as attached, and

Figure 3 is a transverse sectional view taken on line 3—3 of Figures 1 and 2. 60 Like characters of reference indicate corresponding parts throughout the several views.

65 It is well known that in the deep well pumping installations, as for instance pumping oil wells, a casing 10 is employed fitting into the drill-hole and extending downwardly to the bottom of such hole or into the supply of fluid to be pumped. At the bottom of this casing a standing valve 11 is 70 seated. These standing valves are normally of various types but the valve shown in the drawing is of the ball type, a ball 12 being shown mounted in a cage 13, the whole structure being provided with packing of any 75 usual and ordinary type.

Above this standing valve a reciprocating valve is employed in ordinary practice also varying considerably in type. As shown in the drawing a tube 14 is employed having 80 cup leathers 15 at its lower end making a tight fit with the interior of the casing 10 and at its upper end provided with a valve, here shown as of the ball type, a ball 16 being mounted in a ball cage 17. To this structure a sucker-rod 18 of the usual and ordinary type is mounted extending upwardly through the casing to the usual and ordinary means of imparting reciprocating power 85 thereto.

90 At the lower end the tubing 14 is provided with a valve seat 19 through which extends a rod 20 having an enlarged head 21 proportioned to prevent its passing through the central opening of the seat 19. This rod 20 is rigidly secured to the top of the ball cage 95

100 13 in any approved manner, as by the screw-thread connections 22, so that when sufficient stress is exerted upon said rod 20, the standing valve 11 is lifted, as indicated at Figure 2.

105 The length of the rod 20, however, between the head 21 and the ball cage 13 is such as to provide for the normal reciprocation of the working valve, including the tubing 14 and cup leathers 15 in the ordinary pumping operations, so that during such pumping operations the standing valve 11 remains stationary at the bottom of the casing as usual, the rod 20 extending upwardly and sliding freely through the seat 19, offering no resistance to the proper operation 110 and functioning of the working valve in the

lifting of the fluid in the usual and ordinary manner of reciprocating piston pumps. It will be noted, especially from an examination of Figure 3, that the pump rod 20 is 5 provided with a plurality of longitudinal grooves or furrows 23. In the drawing three of these furrows are shown, but it is to be understood that the invention is in no way limited to this exact number. The 10 function of these grooves is, of course, to permit of a freer passage of the fluid upwardly through the valve seat, which normally is out of engagement with the head 21 and only surrounding the rod 20, where- 15 by the grooves add to the carrying capacity of the opening through such seat.

When the organization has been withdrawn and is to be replaced, it is obvious that the two valves will be inserted together 20 and forced downwardly into the casing, the bottom of the tubing 14 engaging the top of the ball cage 13 when necessary to exert force or ramming action upon the standing valve to insure its proper seating in the bot- 25 tom of the casing. By the employment of such an organization the entire structure

may be removed from the casing at a single operation of the withdrawal of the sucker-rod and may be replaced in like manner at a single operation, in the usual well known 30 manner.

What I claim is:

The combination with a well casing of a standing valve located in the bottom of the well casing and provided with a ball cage, 35 a working valve mounted to reciprocate in the casing above the standing valve, a spider carried by the working valve and presenting a central opening, a rod rigidly secured to the ball cage of the standing valve and ex- 40 tending slidably through the central opening of the spider and provided with a head proportioned to engage the spider, said rod being provided with longitudinal furrows in its perimeter.

In testimony whereof I hereunto affix my signature in presence of two witnesses.

WALTER L. GROSS.
